DESIGN FOR A NEGLIGEE

Jacques E. Abraham, New York, N. Y.

Application February 11, 1938, Serial No. 75,052

Term of patent 3½ years

To all whom it may concern:

Be it known that I, Jacques E. Abraham, a citizen of the United States of America, residing in New York city, in the Borough of Manhattan, county and State of New York, have invented a new, original, and ornamental Design for a Negligee, of which the following is a specification, reference being had to the accompanying drawing, forming part thereof, wherein,

Figure 1 is a front view of a negligee showing my new design.

Figure 2 is a rear view of the negligee shown in Figure 1.

The instant design comprises a shirtwaist negligee, the characteristic feature of which resides in the combination of a figured blouse section shirred to a full, solid colored skirt, which is longer in the back than in the front, the waistline shirring extending into the front skirt portion between the specific pocket members as shown.

I claim:

The ornamental design for a negligee, substantially as shown and described.

JACQUES E. ABRAHAM.
